UNITED STATES PATENT OFFICE.

ALLEN P. HOARD, OF TAUNTON, MASSACHUSETTS.

MOUNT FOR PRESERVING RECORDS.

SPECIFICATION forming part of Letters Patent No. 761,964, dated June 7, 1904.

Application filed August 1, 1902. Serial No. 117,913. (No model.)

To all whom it may concern:

Be it known that I, ALLEN P. HOARD, a citizen of the United States, residing at Taunton, in the county of Bristol and State of Massachusetts, have invented a new and useful Improvement in Mounts for Preserving Records, of which the following is a specification.

Records of important events, old documents, rare engravings, and similar written or printed 10 sheets are in their normal condition subject to decay. It is frequently desirable to protect the same against decay or injury caused by handling the sheets, and it is also desirable to bind them into books, arrange them in binders, 15 portfolios, or other receptacles.

The object of my invention is to provide a mount in which record-sheets may be mounted and preserved against the action of the atmosphere or insects and which mounts may be 20 bound in books or placed in portfolios.

The invention consists in the peculiar and novel construction of the mount whereby the record-sheet may be protected, as will be more fully set forth hereinafter.

25 Figure 1 is a plan view of a mount adapted to receive the record-sheet. Fig. 2 is a plan view of the mount containing the record-sheet. Fig. 3 is a plan view of the mount containing the record-sheet covered with a sheet of preservative material. Fig. 4 is a plan view of the completed mount. Fig. 5 is a transverse sectional view showing the parts in their relative positions before being secured together.

In the drawings, *a* indicates the record-sheet, 30 on one or both sides of which a written, drawn, printed, or otherwise produced record desired to be preserved is contained.

b indicates a sheet of paper or other suitable and preferably flexible material of practically the thickness of the record-sheet.

b' is an opening in the sheet, corresponding with the shape and size of the record-sheet, *b²* *b²* the side margins of the sheet *b*, and *b³* *b³* the end margins.

45 *c* indicates sheets of woven silk or silk-gauze treated with paraffin to make the sheet impervious to air, semitransparent, and insect-proof.

d d are strips of thin paper, preferably the tissue-paper of commerce.

The sheet *b* is in the preferred form made of one sheet of paper, in which the opening for the record-sheet *a* is cut out; but the sheet *b* may be formed of four pieces, the two sides *b²* *b²* and the ends *b³* *b³*, as indicated in broken lines, extending perpendicularly across the ends *b³* *b³* in Fig. 1.

In forming the mount one of the sheets *c*, of silk, is pasted on one side of the sheet *b*, so as to cover the opening *b'* and lap over the margins *b²* and *b³*, as shown in Fig. 3 and indicated in broken lines in the other figures. Into the opening *b'* the record-sheet, which has been covered or impregnated with a preserving matter, such as paraffin, is placed and covered 60 with a sheet *c*, of silk, which is pasted on the margins *b²* and *b³*. Both the front and the back sheets *c c* are now pressed on the respective surfaces of the record-sheet *a*, so as to firmly adhere to the same. As the edges *b⁴* of 65 the silk sheets *c c* would be liable to ravel and become injured, the strips *d d* of tissue-paper are pasted over the edges of the silk and the margins *b²* and *b³*, so as to overlap at the corners of the mount, as is shown in Fig. 4.

The mounts may be secured together in a book, secured in a binder, or placed into portfolios. The record will be protected against the action of the air, gases, and the ravages of insects, which will not attack anything impregnated with paraffin.

Having thus described my invention, I claim as new and desire to secure by Letters Patent—

In a mount for preserving records, the combination with the record-sheet *a*, and the margins *b²* *b²* and *b³* *b³*, of the transparent sheets *c c*, and the strips *d d* secured to the margins of the transparent sheets and the margins *b²* and *b³*, as described.

In testimony whereof I have signed my name 90 to this specification in the presence of two subscribing witnesses.

ALLEN P. HOARD.
